FLAT-BED DUPLICATOR

William F. O'Gorman, New York, N. Y.

Application August 24, 1943, Serial No. 499,806

10 Claims. (Cl. 101—126)

My invention relates to a flat bed duplicator and its object is to provide a simple, inexpensive device for making copies from standard stencil sheets. Another object is to provide a hand operated machine of light weight which occupies but little space and is easily transported. These and other objects of the invention will appear in the following specification in which a preferred embodiment of my invention is described, the novel features of which are set forth in the appended claims.

Referring to the drawings:

Figure 1 is a plan view of a duplicator which is made according to and embodies my invention;

Fig. 2 is a side elevation and Fig. 3 a front view of the device shown in Fig. 1.

Fig. 4 is a plan and Fig. 5 a front elevation of a pad which is a part of the device shown in the preceding figures;

Fig. 6 is a side elevation, partly in section and on a larger scale, of one part of the device;

Figs. 7, 8, and 9 are side elevations, partly in section, of parts of the device illustrating the way it is used.

Fig. 10 is a plan view of the inking pad with some of its parts broken away to show the construction;

Fig. 11 is an enlarged section of the ink pad on the line 11—11 of Fig. 10.

10 designates a flat rectangular base with supporting buttons 11 near its corners. This base has a transverse flange 12 across its front end which is somewhat higher than its longitudinal edge 13. 14 is a flat portion at the rear end of the base which is slightly lower than the sides 13. Between the rear edge of the flange 12 and the front edge of the portion 14 and between the sides 13 the base is depressed to form a well 15. This forms a clearance for the inking pad 36 and stencil when the device is not in use and forms a receptacle for a removable flat resilient platen pad 16 (Figs. 4 and 5) when the device is in use.

20 is a flap, preferably formed of sheet metal, pivotally connected to the rear end of the base by a strap hinge 21. This extends over the portion 14 of the base. Its front end extends over the rear end of the platen pad and is bent back, as shown in the drawings and then downwardly to form a flange 23 spaced from the end 22 and somewhat shorter than the width of the well 15 (see Fig. 1). This flange engages the rear end of the platen pad and forms a guide for the paper to be printed as will be more fully described hereinafter.

30 is a flat presser plate pivotally connected to

the flap 20 by a strap hinge 31 on a line spaced from and parallel with the hinge 21. The part of the flap which extends back of the hinge 31 forms a heel 24 which is arranged to be engaged by the rear end 32 of the presser plate. A row of guide screws 35, parallel with the end 32 and spaced therefrom is provided on the under side of the presser plate with clearances provided between their heads and the surface of the plate. An ink pad 36 is secured to the under side of the presser plate by a frame 37 of metal or other suitable material by screws 37A. The construction of the ink pad is an important feature of the invention.

15 Near the other end of the presser plate a transverse groove 38 is formed into which fits a spring clip 39 which is pivoted at 39A to the presser plate. A stencil A is made in the usual way on a typewriter or with a stylus. A standard stencil has a row of keyhole slots near one of its ends. The guide screws 35 are passed through these slots and the stencil stretched across the pad 36 which is previously inked. The other end of the stencil is laid over the groove 38 and the spring clip 39 inserted in the groove with the stencil interposed. The device is then ready for use. It may be closed and kept until ready for use with the ink pad and stencil protected by the sides of the well 14.

20 When the presser plate is raised to the position in which it is shown in Fig. 7, its end 32 engages the heel 24 of the flap and raises the part of the flap in front of the hinge 21. The platen pad 16 is then inserted in the well 15. Raising the presser plate to a substantially vertical position, as shown in Fig. 8, allows the flap to descend until its end 22 rests on the platen pad. There will then be a space between the end 22 of the flap and the top of the platen pad of sufficient width to permit the insertion of a paper B to be printed. The insertion of the paper is limited by the abutment of its edge with the flange 23 and this serves to align the paper with the pad.

25 When the presser plate is lowered, it will press the flange 23 into the platen pad and press the end 22 of the flap onto the paper B and thus prevent the pad and the paper from slipping. It may be seen from Fig. 9 that the initial contact of the stencil with the paper B is at the rear portion of the platen pad. It will be understood that the presser plate is moved manually and that its movement is continued compressing the platen pad until the whole surface of the stencil has been brought into contact with the paper.

30 The presser plate is then raised quickly to the

Fig. 8 position, the printed paper removed, a fresh sheet of paper inserted and the operation repeated. The front end of the presser plate is pushed downwardly to compress the platen pad more than it is compressed at its rear hinged end and so that the pressure on the paper at the front end of the press is greater but for a shorter period of time than it is at the other end.

The inking pad 36 as shown in Figs. 10 and 11 comprises a solid thin flat plate 40 of sheet metal or other suitable material on which is superposed a perforated rigid fibre plate 41 of considerable thickness. Over the plate 41 are one or more sheets of comparatively thin perforated felt 43. The perforations 42 in the plate 41 are of considerable size so that they remove a greater part of the area of the plate for a purpose which I will describe. The perforations 44 in the sheets 43 are much smaller and for a different purpose. Over the outer sheet 43 is an imperforate layer 45 of soft flannel of considerable thickness. The outer layer 46 is of thin silk or the like and the frame 37 which is U-shaped clamps its edges to the plate 40.

The function of this novel inking pad is important for flat printing. Ink is placed on the outer layer 46 as evenly as possible and permeates it and the soft layer 45 immediately under it. When this inked pad is brought into contact with a stencil A some of the ink will be forced through the openings in the stencil onto the paper B. A greater part of the ink will be forced through the perforated sheets 43, which diffuses it laterally into the cells formed in the plate 41 by the perforations 42 therein, backed by the plate 40. These perforations form a plurality of minute reservoirs for holding surplus ink which is fed back through the sheets 43, 43 and the layers 45, 46 during subsequent impressions so that a large number of impressions may be made with one inking.

This simple device is capable of making thousands of copies from a stencil with a single inking of the pad 36. It occupies but little space, and is light and easily transported. I realized that the modifications in the construction and arrangement of the parts may be made within the spirit and scope of the invention and intend no limitations other than those imposed by the following claims.

What is claimed is:

1. A duplicator comprising a flat base with upstanding edges forming a well, a presser plate pivotally connected with the base near the rear end of the base, an ink pad secured to the presser plate arranged to fit with clearance between said edges, means for attaching a stencil to the presser plate over the ink pad, and a removable platen pad arranged to be placed in said well.

2. A duplicator comprising a flat base with upstanding edges forming a well, a presser plate pivotally connected with the base near the rear end of the base, an ink pad secured to the presser plate arranged to fit with clearance between said edges, means for attaching a stencil to the presser plate over the ink pad, said presser plate being movable to and from a position spaced from and approximately parallel with the base, and a removable platen pad arranged to be placed in said well.

3. A duplicator comprising a flat base with upstanding edges forming a well, a presser plate pivotally connected with the base near the rear end of the base, an ink pad secured to the presser

plate arranged to fit with clearance between said edges, and means for attaching a stencil to the presser plate over the ink pad, said presser plate being movable into a position spaced from and approximately parallel with the base, a removable resilient platen pad arranged to be placed in said well the thickness of the platen pad being greater than the distance from the bottom of the well to the ink pad when the presser plate is in said approximate parallelism with the base.

4. A duplicator comprising a flat base, a platen pad, a flap pivotally attached to the rear end of the base having a part extending over the rear end of the platen pad, a presser plate pivotally attached to the flap intermediate the pivotal attachment of the flap to the base and said extending part of the flap, an ink pad secured to the presser plate and means for attaching a stencil to the presser plate over the ink pad to the flap, and the part of the flap back of said pivotal attachment extending beyond the rear edge of the presser plate and arranged to be engaged thereby.

5. A duplicator comprising a flat base, a platen pad, a flap pivotally attached to the rear end of the base, a presser plate pivotally attached to the flap in front of the pivotal attachment of the flap to the base, said flap having a downwardly extending flange arranged to engage the platen pad and to form a paper guide.

6. A duplicator comprising a flat base with upstanding edges forming a well, a flap pivotally attached to the rear end of the base, a presser plate pivotally attached to the flap arranged to fit with clearance between said edges, an ink pad secured to the presser plate and means for attaching a stencil to the presser plate over the ink pad, said presser plate being movable into a position spaced from and approximately parallel with the base, a removable resilient platen pad arranged to be placed in said well, the thickness of the platen pad being greater than the distance from the bottom of the well to the ink pad when the presser plate is in said approximate parallelism with the base.

7. A duplicator comprising a flat base with upstanding edges forming a well, a flap pivotally attached to the rear end of the base, a presser platen pivotally attached to the flap in front of the pivotal attachment of the flap to the base, an ink pad secured to the presser plate arranged to fit with clearance between said edges and means for attaching a stencil to the presser plate over the ink pad, the part of the flap in front of the pivotal attachment thereof to the base extending over the rear end of the platen pad and the part of the pad back of said pivotal attachment extending beyond the rear edge of the presser plate and arranged to be engaged thereby, said presser plate being movable into a position spaced from and approximately parallel with the base, the outer dimensions of the ink pad being less than the inner dimensions of the well, a removable platen pad arranged to be placed in said well, the thickness of the platen pad being greater than the distance from the bottom of the well to the ink pad when the presser plate is in said approximate parallelism with the base.

8. A duplicator comprising a flat base with upstanding edges forming a well, a flap pivotally attached to the rear end of the base, a presser platen pivotally attached to the flap in front of the pivotal attachment of the flap to the base, an ink pad secured to the presser plate arranged to fit with clearance between said edges, and

means for attaching a stencil to the presser plate over the ink pad, a removable resilient platen pad arranged to be placed in said well, the part of the flap in front of the pivotal attachment thereof to the base extending over the rear end of the platen pad and the part of the pad back of said pivotal attachment extending beyond the rear edge of the presser plate and arranged to be engaged thereby, said flap having a downwardly extending flange arranged to engage the platen pad and to form a paper guide.

9. A duplicator comprising a flat base with upstanding edges forming a well, a presser plate pivotally connected with the base near the rear end of the base, an ink pad secured to the presser plate arranged to fit with clearance between said edges, a removable platen pad arranged to be placed in said well, said ink pad comprising a

flat imperforate plate, a flat perforate plate of material thickness thereon constructed to form a plurality of ink receiving cells and an outer layer of permeable sheet material.

10. A duplicator comprising a flat base with upstanding edges forming a well, a presser plate pivotally connected with the base near the rear end of the base, an ink pad secured to the presser plate arranged to fit with clearance between said edges, a removable platen pad arranged to be placed in said well, said ink pad comprising a flat imperforate plate, a flat perforate plate of material thickness thereon constructed to form a plurality of ink receiving cells, a thin perforated differing sheet, a soft permeable bed layer, and a thin outer layer of permeable sheet material.

WILLIAM F. O'GORMAN.
